SKI BINDING

Arild Schlytter, Fornebu, near Oslo, Norway

Application December 18, 1947, Serial No. 792,441
In Norway November 19, 1943

Section 1, Public Law 690, August 8, 1946
Patent expires November 19, 1963

1 Claim. (Cl. 280—11.35)

1

The present invention relates to ski bindings of the type wherein the strap securing the shoe of the user to the ski in part consists of a wire rope. In straps of this type it is previously known to effect the length adjustment of the strap by providing a number of stop rings, balls, pearls or the like slidably arranged on the wire rope, a fixed enlargement being arranged at the end of the wire rope, which enlargement when the wire rope is subjected to tension engages the rings or the like thereby transferring the tension through the same to the holding means associated with the other part of the strap, preferably the heel band or strap. The effective length of the strap may then be adjusted by placing a greater or smaller number of rings or the like between the end of the wire rope or the enlargement provided on the same and the said holding means.

In known embodiments of such straps, the rings or the like situated on the side of the holding device opposite to the end of the wire rope on which the enlargement is situated, were freely slideable along the wire rope whereby the wire rope, when untightened, for instance when the skis are carried or transported, may slide in the holding device and tend to slip out of the same, if the holding device is not specially built to meet this contingency.

It is the object of the present invention to provide an arrangement preventing the said possibility of free movement of the rings or the like along the wire rope and at the same time permitting the use of a holding device which is simpler in construction and which enables a quicker and easier hooking and de-hooking of the wire rope, for instance for the purpose of adjustment as compared with the devices previously used.

According to the invention this object is achieved by providing the wire rope with a helically wound elastic wrapping which by pressing against the rings situated outside of the holding device or against the holding device itself, exercise a stretching action on the wire rope, thereby maintaining the same in a taut condition preventing the disengagement of the rings from the holding device even when the ski binding is out of use, as by transport of the ski. The holding device conveniently is made in the form of a sleeve or is provided with a sleeve of an interior diameter corresponding to that of the rings in such a manner that a ring may be introduced into the sleeve from one end or through an aperture in the sleeve wall to abut against a throat or abutment at the other end of the sleeve and the sleeve is provided with a longitudinal slot

5 of such width, that only the wire rope may be introduced into the sleeve when the rings are so displaced that a portion of the wire rope of sufficient length is uncovered. Conveniently the holding device is secured to one end of the heel strap.

10 On the accompanying drawing an embodiment is shown of a strap provided with length adjusting means in accordance with the present invention. In Figure 1 the entire strap is shown as seen from above, and Figure 2 is a vertical longitudinal section of the holding device. The strap is here made in the form of a continuous loop, but may of course be made of two separate side portions, each of them being provided with length adjusting means according to the invention.

15 Referring to the drawing 1 represents the wire rope, 2 the enlargement at one end of the wire rope and 3 the pressure rings which are passed round the wire rope and are slideable on the same. The end of the wire rope carrying the said rings is connected to the heel strap 4 by the holding device generally represented by 11, the end holding device being provided with external screw threads which in a manner known per se may engage the helically wound wire constituting the heel strap 4, the other end of the wire rope 1 being connected to the heel strap 4 by means of a conventional tightening device 6.

20 The sleeve 5 of the holding device 11 is provided with an aperture 7 through which the rings 3 may be introduced and be brought to abut against a throat or flange 8 at the other end of the sleeve. The sleeve 5 is provided with a longitudinal slot 9 through which the wire rope proper may be introduced when the rings 3 are slid along the wire rope so as to uncover a sufficient length of the wire rope. By the tightening 25 of the wire rope 1 by means of the tightener 6 the tension is transmitted to the heel strap 4 by the engagement of the enlargement 2 at the end of the wire rope 1 with the rings 3 situated between the enlargement 2 and the throat 8 at the end of the sleeve 5. If the effective length of the strap is shortened by placing a greater number of rings 3 between the enlargement 2 and the throat 8, the end of the wire rope carrying the said rings 3 may extend more or less into the heel strap 4. 10 represents the helical wrapping of the wire rope 1 which offers a good protection of the wire rope 1 and also, according to the invention, serves to keep such rings 3 which are situated outside of the holding device 11 pressed against the end face of the said device

thereby maintaining the wire rope tight so as to effectively prevent the disengagement of the wire rope with the rings, for instance when the skis are carried.

What I claim is:

A ski binding strap serving to secure the shoe to the ski, comprising in combination a wire rope and a heel strap, connecting devices for connecting the ends of the wire rope to the ends of the heel strap, one of the said connecting devices consisting of a sleeve secured to the end of the heel strap and detachably holding the end of the wire rope, the outer end of the said sleeve being provided with an inwardly bent flange, the end of the wire rope being provided with an enlargement adapted to engage the said flange, a number of rings slidable on the end portion of the wire rope and adapted to be disposed in the said sleeve between the said flange of the same and

the said enlargement on the end of the wire rope, and a helical spring coiled round the wire rope outside of the sleeve, exercising a pressure against rings situated outside of the sleeve, thereby maintaining the wire rope in a tight condition.
